(57) **CLAIM**

The ornamental design for a gaming chair as shown and described.

DESCRIPTION

FIG. 1 is a top front left perspective view of my new design; FIG. 2 is a bottom rear right perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detailed view of the area labeled "9" in FIG. 1;

FIG. 10 is an enlarged detailed view of the area labeled "10" in FIG. 1;

FIG. 11 is an enlarged detailed view of the area labeled "11" in FIG. 2;

FIG. 12 is an enlarged detailed view of the area labeled "12" in FIG. 2;

FIG. 13 is an enlarged detailed view of the area labeled "13" in FIG. 3;

FIG. 14 is an enlarged detailed view of the area labeled "14" in FIG. 7; and,

FIG. 15 is an enlarged detailed view of the area labeled "15" in FIG. 8.

The evenly dashed broken lines show portions of the article that form no part of the claimed design. The dot-dash broken lines illustrate the border of the enlarged detailed view and form no part of the claimed design.

1 Claim, 15 Drawing Sheets
